PAYROLL TIME CALCULATOR

Solomon Linowitz, Brooklyn, N. Y.

Application September 7, 1946, Serial No. 695,413

9 Claims. (Cl. 235—83)

1

This invention relates to pay roll time calculators wherein the time worked by an employee, even though gaps in his time for lunch hours have been had, can readily be ascertained.

It is an object of the present invention to provide a simple hand calculator that can be rested upon the desk of a time clerk and by the simple manipulation of two relatively movable parts, a reading of the total hours worked during the day can be easily reckoned.

According to the invention, a differential gear mechanism is connected between a knob and a dial to obtain, when the knob is rotated to register its pointer on a fixed scale an opposite rotation of the dial. When the knob pointer comes to rest on the time at which the employee stopped work a reading of the total hours and fractions thereof can be read on the dial which has been rotated at the index. The fixed dial is held fixed only while the calculation is being made. If it is desired to add to the original hours, hours in the day which have been later worked by the employee, the fixed dial bearing the time can be adjusted to register the new starting point with the pointer. Thereafter the pointer is turned to the next stopping point. The new hours will be added to the first hours and the total hours employed for both workings will now be read on the oppositely rotated scale.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is a front elevational view of one form of calculator embodying the features of the present invention.

Fig. 2 is a cross sectional view, in side elevation, of the calculator of Fig. 1, viewed along the line 2—2 thereof looking in the direction of its arrows.

Fig. 3 is a detail side elevational view of the main drive shaft.

Fig. 4 is a detail side elevational view of the sleeve relatively rotatable on the main drive shaft having one gear and the rotating dial connected thereto.

Fig. 5 is a side elevational view of the bearing sleeve carried by the frame in which the sleeve shown in Fig. 4 is journaled.

Fig. 6 is a fragmentary face view of the dials and indicators showing the reading when the pointer has been moved to the stopping time of the worker.

2

Fig. 7 is a fragmentary face view of the dials and indicators showing the reading after the fixed dial has been adjusted and the later hours added to the rotating dial as a result of the knob having been moved to the later stopping time.

Fig. 8 is a perspective view of a modified form of calculator which has an inclined front and is mounted in a casing.

Fig. 9 is a cross sectional view, in elevation, taken along the line 9—9 of Fig. 8 and looking in the direction of the arrows thereof.

Fig. 10 is a front face view of the form shown in Fig. 8 with casing portions broken away to show certain of the rotating parts in full.

Fig. 11 is a top plan view of another form of the invention employing two plate gears rotatable about different axes.

Fig. 12 is a longitudinal cross sectional view taken along the line 12—12 of Fig. 11, looking in the direction of the arrows thereof.

Fig. 13 is a transverse cross sectional view taken along the line 13—13 of Fig. 11, looking in the direction of the arrows thereof.

Referring now to Figs. 1 to 7, description will be made of the first form of the invention wherein 15 indicates a base on which there is stood upright two horizontally spaced supporting members 16 and 17. These members are held in their horizontally spaced relationship at their upper ends by vertically spaced spacer bars 18 and 19. The lower ends of the members have outwardly turned flanges 21 which are secured to the base by screws 22.

In the front supporting member there is fitted tightly a bearing sleeve 23 shouldered, as indicated at 24, to be inserted through the supporting member 16 from its rear face. This member is shown in detail in Fig. 5. The front end of the sleeve 23 has an annular recess 25 adapted to receive a spring lock ring 26. Over the sleeve 23 there is disposed a curved leaf spring 27 bearing against the front face of the member 16. An external dial 28 is fitted on the sleeve 23 and is held in place after first compressing the leaf spring 27 and engaging the lock ring 26. The dial 28 is retained in its adjusted position by the spring 27. However, while time is being calculated it remains stationary, the other parts being the only ones moved at this time.

The time dial 28 has a circular recess 31 adapted to receive a rotating dial 32 which is press fitted on a knurled portion 33 (Fig. 4), of a sleeve 35 journaled in the sleeve 23 and hollowed to receive a main drive shaft 36. Keyed to the front end of this drive shaft is a knob 37 having a pointer 38 adapted to register with the scale on the time dial 28. The opposite end of

the shaft is journaled in a bearing sleeve 39 secured to the rear supporting member 11. Immediately in front of the rear supporting member 11 there is fixed to the shaft a bevel plate gear 41 by a pin 42.

This bevel plate gear 41 forms part of a gear mechanism which includes further a bevel pinion 43 pivoted about a vertical axle and journaled in the spacer bar 18. This pinion is adapted to be driven by the plate gear 41 as the knob 37 is turned and drives in an opposite direction from the plate gear 41 a second plate gear 44 which is tightly fitted upon a reduced end portion of hollow sleeve 35 to drive sleeve 35 and the rotating dial in a reverse direction from which the knob is turned.

The time dial 28 (Fig. 1), is marked off in twenty-four parts to represent the hours of the day. Starting with twelve midnight at the top of the dial the marks are numbered up to twelve noon which will appear at the bottom of the dial. Beginning from twelve noon the marks are numbered from one to twelve midnight. The spaces between marks can be divided off into fifteen minute periods. Extending up from the base 15 and secured thereto by the same screws 22 that secure the flange 21 of the front supporting member 16 therewith, is a transparent member 41 having a pointed upper end 48 with an indicating line 49 thereon. Also on this pointed end is a window 51 through which numbers on the rotating dial 32 will appear.

Assuming that the man starts work at twelve o'clock midnight the time dial 28 will be adjusted to have the twelve midnight mark on the indicator line 49. The rotatable dial 32 is numbered from one to twenty-four and so indicated with reference to marks on the periphery of the same. Between marks there may be smaller marks indicating fractions of the hour. The rotating dial is aligned with the indicator line 49 so that its mark 24 will appear through the window 51. The pointer 38 is so arranged in its connection with the rotating dial 32 that it will automatically arrive at the indicator line.

Assuming that the man works until four o'clock the pointer 38 will be turned to the number four on the time dial 28. A reading of four hours will be indicated through the window 51 (Fig. 6). Thereafter assuming the man has had a rest period of one hour before starting work again, the time dial 28 will be adjusted so that its five o'clock mark registers with the pointer 38. If he works from five to seven the pointer will be turned to the seven on the time dial 28 as illustrated in Fig. 7. These two hours will be added to the original four and a six will appear in the window 51 to indicate the total number of hours which the man has worked.

Referring now to the form of the invention shown in Figs. 8, 9 and 10, a slightly different arrangement will be found. Instead of the inner dial being rotated as the knob is turned the outer dial is rotated and the reading taken from the same. The entire mechanism is pitched at an angle so that the dials appear on inclined face.

The entire mechanism is housed in a casing 53 having an inclined front wall 54. The bottom supports an angularly positioned U-shaped member 55 in one part of which is journaled a pinion 56 and in the other part of which there is journaled a shaft 57. This shaft has a plate gear 58 connected to it by a pin 59. The forward end of the shaft has a pointer 61 which is moved by a handle projection 62. As the pointer is adjusted

to an inner time dial 72 the shaft 57 is rotated, gears 56 and 58 are turned and so is a bevel plate gear 64 journaled on the support member 55 and connected through arm 65 with a rotating number of hours dial 66 to show through a window 67 in a cover plate 73 on the front of the instrument.

This plate 68 is indented or depressed at its center portion to provide a recess 69 on its front face for housing three spur gears 71 and a time dial 72 having gear teeth on its outer periphery matching with the spur gears. The gear dial 72 is accordingly held centered by the spur gears 71 journaled to the plate 68. A final cover plate 73 having an opening 74 extends over the spur gears and the toothed dial.

The dial 72 is set to an indicator mark 75 by grasping and moving one of its handles 16. Pointer 61 is grasped by its handle 62 and turned to the time when the employee stops work. By illustration the indicator 61 has been moved to four o'clock on the inner dial. Through the window 67 there will appear the number of hours which the employee has worked from twelve at night to four o'clock in the morning. This number will be four. Added hours can be calculated by adjusting the parts in the same manner as the parts of the first form were adjusted.

Referring now to Figs. 11, 12 and 13, 81 represents a long rectangular shaped casing made of two parts 82 and 83 adapted to be connected together through spacing members 84 by the insertion of screws 85 thereinto. Within the casing 81 there is journaled a shaft 85 having a plate gear 86 thereon. The shaft 85 extends outwardly through the top of the casing and through a sleeve 87 journaled upon the shaft 85 and in the casing part 82. On the outer end of the shaft there is fixed a knob 88 and a pointer 89. Secured to the sleeve 87 by a spring 91 and a shoulder 92 of the sleeve is a time disc 93 which can be adjusted to any station to indicate by alignment with the index 89 the starting time of the worker. Thereafter the knob and gear 86 is turned until the pointer reaches the stopping time.

Also journaled in the casing 81 is a shaft 94 having a plate gear 95 meshing with the plate gear 86. This plate gear 95 will be turned in the opposite direction from that of plate gear 86. An hour dial 96 is secured to the shaft 94 which will bear a reading through an opening 97 in the casing part 82. The number of hours worked will be read directly from the dial 96. When the device is used upon a flat surface such as a desk top, it is supported upon inclined top portions 98 of a support 99.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A pay roll time calculator comprising supporting members, a time dial journaled for adjustment on said members, a fixed indicating mark on said time dial, an hour registry dial, a shaft journaled on the supporting members, a pointer fixed to the shaft and adapted to register with the scale of the time dial, and means operatively connected between the shaft and the hour dial for effecting rotation of the dial in

an opposite direction to the rotation of the shaft, a fixed indicating mark on the calculator from which the number of hours which have been worked may be read off the rotated or hour dial.

2. A pay roll time calculator comprising supporting members, a time dial journalled for adjustment on said members, a fixed indicating mark on said time dial, an hour registry dial concentric with the time dial, a shaft journalled on the supporting members, a pointer fixed to the shaft and adapted to register with the scale of the dials, and means operatively connected between the shaft and the hour dial for effecting rotation of the dial in an opposite direction to the rotation of the shaft, a fixed indicating mark on the calculator from which the number of hours which have been worked may be read off the rotated or hour dial, said means connected between the shaft and the hour dial comprising gearing including two plate gears concentric with the shaft and an interconnected pinion gear journalled for rotation on the supporting members about a vertical axis.

3. A pay roll time calculator comprising supporting members, a time dial journalled for adjustment on said members, a fixed indicating mark on said time dial, an hour registry dial concentric with the time dial, a shaft journalled on the supporting members, a pointer fixed to the shaft and adapted to register with the scale of the dials, and means operatively connected between the shaft and the hour dial for effecting rotation of the dial in an opposite direction to the rotation of the shaft, a fixed indicating mark on the calculator from which the number of hours which have been worked may be read off the rotated or hour dial, a knob connected with the pointer and the shaft to effect the turning movement of the shaft.

4. A pay roll time calculator comprising supporting members, a time dial journalled for adjustment on said members, a fixed indicating mark on said time dial, an hour registry dial concentric with the time dial, a shaft journalled on the supporting members, a pointer fixed to the shaft and adapted to register with the scale of the dials, and means operatively connected between the shaft and the hour dial for effecting rotation of the dial in an opposite direction to the rotation of the shaft, a fixed indicating mark on the calculator from which the number of hours which have been worked may be read off the rotated or hour dial, said time dial having a recess therein and said hour registering dial lying within the recess of the time dial so that its face will lie flush with the front face of the time dial.

5. A pay roll time calculator comprising supporting members, a time dial journalled for adjustment on said members, an hour registry dial concentric with the time dial, a shaft journalled on the supporting members, a pointer fixed to the shaft and adapted to register with the scale of the dials, and means operatively connected between the shaft and the hour dial for effecting rotation of the dial in an opposite direction to the rotation of the shaft, a fixed indicating mark on the calculator from which the number of hours which have been worked may be read off the rotated or hour dial, said time dial having a recess therein and said hour registering dial lying within the recess of the time dial so that its face will lie flush with the front face of the time dial, a knob connected with the pointer and the shaft to effect the turning movement of the shaft.

6. A pay roll time calculator comprising supporting members, a time dial journalled for adjustment on said members, an hour registry dial concentric with the time dial, a shaft journalled on the supporting members, a pointer fixed to the shaft and adapted to register with the scale of the dials, and means operatively connected between the shaft and the hour dial for effecting rotation of the dial in an opposite direction to the rotation of the shaft, a fixed indicating mark on the calculator from which the number of hours which have been worked may be read off the rotated or hour dial, said time registering dial being concentric with the hour registering dial and lying within the center of the same, the number of hours being taken from the external dial.

7. A pay roll time calculator comprising supporting members, a time dial journalled for adjustment on said members, an hour registry dial concentric with the time dial, a shaft journalled on the supporting members, a pointer fixed to the shaft and adapted to register with the scale of the dials, and means operatively connected between the shaft and the hour dial for effecting rotation of the dial in an opposite direction to the rotation of the shaft, a fixed indicating mark on the calculator from which the number of hours which have been worked may be read off the rotated or hour dial, said means connected between the shaft and the hour dial comprising gearing including two plate gears concentric with the shaft and an interconnected pinion gear journalled for rotation on the supporting members about a vertical axis.

8. A pay roll time calculator comprising a base, upstanding horizontally spaced supporting members secured to the base, a bearing sleeve fixed to one of the members, a journal sleeve journalled in the bearing sleeve, a time dial fixed to the journal sleeve, a shaft journalled in the journal sleeve and in the other of said members, a plate gear fixed to said shaft to be rotated thereby, a pinion meshing with the plate gear and journalled on the supporting members, a second plate gear meshing with the bevel pinion and journalled on said journal sleeve, an hour dial fixed to the sleeve, whereby said hour dial is adapted to operate in reverse direction to the shaft, and a pointer on the shaft adapted to register with marks on both of said dials.

9. A pay roll time calculator comprising supporting members, a time dial journalled for adjustment on said members, a fixed indicating mark on said time dial, an hour registry dial, a shaft journalled on the supporting members, a pointer fixed to the shaft and adapted to register with the scale of the time dial, and means operatively connected between the shaft and the hour dial for effecting rotation of the dial in an opposite direction to the rotation of the shaft, a fixed indicating mark on the calculator from which the number of hours which have been worked may be read off the rotated or hour dial, said means connected between the shaft and the hour dial comprising two plate gears meshing with one another and rotatable about axis laterally spaced from one another.
